UNITED STATES PATENT OFFICE.

KRAFT BOOTH, OF PHILADELPHIA, PENNSYLVANIA, ASSIGNOR TO
GILLINDER & SONS, INC., OF PHILADELPHIA, PENNSYLVANIA.

DESIGN FOR AN ARTIFICIAL-LIGHT REFLECTOR.

No. 38,188.

Specification for Design.

Patented Aug. 21, 1906.

Application filed June 27, 1906. Serial No. 323,743. Term of patent 7 years.

To all whom it may concern:

Be it known that I, KRAFT BOOTH, a citizen of the United States, and a resident of the city of Philadelphia, in the county of Philadelphia and State of Pennsylvania, have invented a new, original, and ornamental Design for an Artificial-Light Reflector, of which the following is a specification, reference being had to the accompanying drawings, in which--

Figure 1 is a view in side elevation of an

artificial-light reflector, showing my design. Fig. 2 is a top or plan view, and Fig. 3 an inverted plan view, thereof.

I claim as my invention—

The ornamental design for an artificial-light reflector, as shown.

KRAFT BOOTH.
